DUPLICATING MACHINE

James K. Duncan, Chicago, Ill., assignor to Ditto
Incorporated, Chicago, Ill., a corporation of
West Virginia

Application December 3, 1931. Serial No. 578,644

15 Claims. (Cl. 101—133)

The invention relates to duplicating machines of the type employing a gelatin matrix over which is adapted to travel a platen carriage, and has reference more particularly to improved means for rotating the impression roller upon linear movement of the carriage.

In the above type of machines the platen carriage travels back and forth over the surface of the gelatinized duplicating band for first 10 pressing the master and copy sheets upon the surface of the gelatin and for subsequently stripping them from gelatin, the actual impression member comprising a rubber roller journaled in the carriage and rotated by the travel of the carriage. The spindle of this roller has heretofore 15 been equipped with a pulley or grooved wheel around which is passed a cable, the cable being fixed at its ends to the frame of the machine, the construction serving to positively rotate the roller 20 during the travel of the carriage so as to not only insure feeding of the paper sheet and discharge of the same, but also to impress the sheet upon the duplicating band.

One of the many disadvantages due to the use 25 of the cable was the fact that, although the impression roller was driven at the desired speed during linear movement of the carriage, the roller remains stationary during the raising and lowering movements to locate the roller in released 30 and depressed positions respectively. In operation to initially impress the paper upon the duplicating band to begin a printing stroke, the roller thus fed the sheet towards the margin bar or stop, causing the sheet to loop in front of the 35 roller. Such conditions adversely effected the operating efficiency of the machine, especially when card stock was used, since the marginal edge of the same would be materially bent, destroying the surface of the card. Also the use 40 of the cable prevented the impression roller from being easily removed from the machine to allow cleaning of the same and the life of the cable, due to constant and severe use, was very short.

An object of the present invention is to provide 45 improved means for driving the impression roller of hektograph machines, which will be simple in construction permitting the parts to be easily assembled and disassembled for cleaning purposes, positive in operation and which will 50 adapt itself to all the requirements for hektograph machine work.

A yet further object is to provide a gear driven 55 impression roller, the construction being able to withstand severe usage and thus having a long life.

A yet further object of the present invention is to provide improved means for positively rotating the impression roller upon linear travel of the carriage, the rotation of the roller having a definite relation to the extent of travel of the carriage to maintain a slight drag or tension upon the paper sheet as the same is being impressed 60 on the gelatin surface so as to iron out any wrinkles in the sheet, thus insuring a perfect impression on each printing operation. 65

A yet further object is to provide improved means for rotating the impression roller upon linear movement being imparted to the carriage, the means including connecting gearing between the roller and stationary means disposed adjacent 70 the carriage.

A yet further object is the provision of means for positively rotating the impression roller, the rotation of the roller being under control at all 75 times.

A still further object is to provide improved means for rotating the impression roller, including 80 gearing connecting the roller with a stationary back bar located adjacent the carriage, whereby the roller is positively rotated upon linear movement of the travel and wherein the gearing functions to cause rotation of the impression roller during vertical movements of the same to locate the roller in released or depressed position. 85

Accordingly, another object of the invention is the provision of improved means for driving the impression roller, the roller being rotated in a direction as the same is lowered onto impression, such that the roller will feed the inserted sheet 90 outwardly away from the margin bar at a rate slightly less than the downward travel the roller tends to feed towards the margin bar.

A yet further object is to provide a gear drive 95 for the impression roller driven from a geared shaft housed within the slide extension on the carriage frame, the construction permitting a pivotal connection between the extension and the carriage frame so that the frame will automatically center itself upon the platen surface. 100

With these and various other objects in view, the invention may consist of certain novel features of construction and operation, as will be more fully described and particularly pointed out in the specification, drawings and claims appended hereto. 105

In the drawings, which illustrate an embodiment of the device and wherein like reference characters are used to designate like parts—

Figure 1 is an elevational view of the complete 110

machine showing the same constructed in accordance with the present invention;

Figure 2 is a detail sectional view showing the gearing for driving the impression roller;

5 Figure 3 is a sectional view taken on the plane indicated by line 3—3 of Figure 1;

Figure 4 is a sectional view taken along the plane indicated by line 4—4 of Figure 2;

10 Figure 5 is a detail view showing the stationary plate member;

Figure 6 is a detail view showing the movable plate member; and

15 Fig. 7 is a fragmentary section taken longitudinally through the machine to illustrate the action of impression and pressure rollers with which the machine is equipped.

Referring to the drawings and particularly to Figures 1 and 3, the machine is shown as comprising spaced frame members 10 provided with 20 tracks 11 upon their upper surface and supports 12 at the lower end thereof for supporting the machine upon a base or any suitable table. The frames 10 are held in spaced relation by tie bars and have suitably journaled therein spindles 13 25 upon which is wound the gelatin duplicating band 14, the band being supported upon the flat platen 15 suitably secured to the side frames through means of the shoulders 16 integrally formed thereon.

30 Adapted to travel back and forth over that surface of the gelatin band supported upon the platen 15 is a carriage 18 including a carriage frame formed of spaced parallel side members 19 and 20, end walls 21 and 22, suitably connected to the side members, and a carriage extension 23 in the form of a yoke provided with arms 24 and 25, the same being secured respectively through suitable studs 26 to the side members 19 and 20. The extension 23 has sliding engagement upon a rod 27 mounted for rotation upon one of the frames 10 by means of brackets 28 integrally formed with the frame. Located upon one end of bar 27 is an adjustable stop 29, while at its extreme opposite end is a stationary stop 30. Secured to the carriage frame are adjustable depending studs 31 resting on the tracks 11 for supporting the carriage and permitting linear movement of the same over the platen 15.

50 Mounted within the end walls 21 and 22 is a shaft 32 adapted to pivotally support within the frame the handle arm 33 having integrally or suitably secured to each end thereof extensions 34 and provided with an operating handle 35. Journaled within the extensions 34 is a shaft 39 55 carrying an impression roller 36, one end of the shaft having suitably keyed thereto a pinion 37. The impression roller 36 is adapted to be raised and lowered since handle arm 33 is pivoted within the carriage frame and is rocked through actuation of handle 35, and for the purpose the lower portion of the end walls 21 and 22 are slotted as at 38 for permitting vertical movements of shaft 39 of the roller. During operative or depressed position of the impression roller the same 60 is in engagement with pressure roller 40 pivotally mounted within the carriage frame and spring pressed towards the impression roller by means of the spring 41. With the impression roller in released position a sheet of paper is inserted between the roller from copy holder 42 and as the impression roller is lowered onto impression, the paper is held between the same and the pressure roller 40, causing feeding of the sheet and impressing the same upon the surface of the gelatin band, either to impart to or

to receive therefrom an impression, as is common and well known in machines of this class.

As shown in Figures 3 and 4 the rod 27 is provided on its upper surface with a rack bar 43, while adapted to have slideable movement upon the bar 27 is a housing 44 within which is journaled the shaft 45 having suitably keyed thereto and disposed within spaced arms of the housing a gear 46. Shaft 45 is positioned in the housing a definite distance from the teeth of the rack bar 43 and thus the gear 46 is mounted in definite relationship to the rack bar and is supported by means of the housing upon the bar 27, the construction being such that the pitch line of the teeth on gear 46 and the pitch line of the teeth on the rack bar 43 are tangent to each other thus insuring free and noiseless operation of the gear upon the rack. To the free end of shaft 45 is suitably keyed the pinion 47, the washer 48 being mounted on the shaft between the gear and the housing and adjustably positioned thereon by means of lock washers 50. The shaft 45 terminates adjacent the end wall 21 and is provided with a bore 51 for accommodating the projecting end of shaft 32. The shaft 45 is in this manner supported at its inner end upon the carriage frame, while permitting independent rotation of the same and shaft 32.

Rigidly secured to the end wall 21, as shown in Figure 2, is a plate 53 having a substantially vertical slot 54 provided therein for permitting vertical movements of the impression roller shaft 39 and being additionally provided with opening 55 for receiving the end of shaft 45. Pin 56 serves to secure the plate to the end wall. Located upon the outer surface of the plate 53 is a movable plate 57, having slot 58 formed therein for receiving the impression roller shaft and openings 60 and 61 respectively, the former serving to receive the end of shaft 45, while the latter accommodates the stud 62 upon which is rotatably mounted the intermediate gear 63 having meshing engagement, as shown in Figure 2, with pinion 47 keyed to shaft 45 and pinion 37 keyed to the impression roller shaft 39. It will be seen that by reason of the above construction, upon linear movement being imparted to the carriage, gear 46 will be rotated to drive shaft 45 and through the chain of gearing corresponding rotations will be imparted to pinion 37 and the impression roller 36. By selecting pinions and gears of predetermined size, any peripheral speed of the impression roller can be secured as desired. For instance an increase in the size of pinion 47 will function to increase the peripheral speed of the impression roller 36 beyond that which the roller would ordinarily have were it free to rotate upon the surface of the gelatin during movement of the carriage. In like manner it will be apparent that the peripheral speed of the impression roller can be made less than that which it would have were it free to rotate, this latter condition being preferable, since a slight drag or tension is given to the paper sheet as the same is impressed upon the surface of the gelatin so that all wrinkles in the sheet are ironed out.

By the chain of gearing connecting the impression roller with the stationary rack bar 43 the rotations of the roller are not only controlled during linear movement of the carriage but also as the roller is oscillated vertically to locate the same in released or depressed position. As shown in Figure 2, should the impression roller be elevated, the movement would be imparted to plate 57 which would pivot around shaft 45, carrying

with it the intermediate gear 63. This movement of plate and gear around pinion 47 would impart to the gear counter-clockwise rotation. With the impression roller in elevated position a sheet of paper is inserted between the same and the pressure roller 40 until the leading edge of the same engages the margin bar 65. The impression roller is now ready to be depressed into operative position, which movement will impart to gear 63 a clockwise rotation and to pinion 37 meshing therewith a counter-clockwise rotation. The counter-clockwise rotation of the impression roller is immaterial until the same contacts the roller 40, whereupon the sheet of paper held between the rollers is fed outwardly by the rotation of the impression roller. The feeding of the paper outward and thus away from the margin bar takes place at a rate less than the downward travel of the roller functions to feed the sheet towards the margin bar, the result being to maintain the leading edge in constant engagement with the margin bar but to prevent the formation of an excessive loop of the sheet immediately in advance of the impression roller. With the impression roller holding the marginal edge of the sheet firmly against the surface of the gelatin band, it will be seen that upon imparting linear movement to the carriage the impression roller will be rotated in a clockwise direction to properly feed and impress the sheet upon the gelatin, as is common and well known in hectograph machine construction.

The construction of the present invention results in controlling the rotation of the impression roller at all times with the resulting advantages above enumerated and with the additional advantage that by merely selecting the proper size of gears and pinions the speed of rotation during linear movement of the carriage can be varied without affecting the degree of rotation of the roller during vertical movements of the same. It is also to be noted that with the carriage in forward position against the stop 30 the same is maintained against the stop by the actuation of handle 35 to locate the impression roller in depressed position. Movement in this direction will, as described, rotate gear 63 in clockwise direction and as the gear rotates around pinion 47 there is a tendency to rotate the pinion in a counter-clockwise direction, which, through shaft 45 and connected gear 46, functions to hold the carriage in engagement against the stop.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

60 I claim:

1. In a duplicating machine, a traveling platen carriage, an impression roller, gearing carried by said carriage and operatively connected to said impression roller, a rack bar disposed adjacent said carriage, a housing slidable on said bar and providing journaling means for a driving shaft, and gears on said shaft one of which meshes with the rack bar and the other of which meshes with said gearing.

70 2. In a duplicating machine, a carriage comprising end frame members, a handle arm pivotally mounted within said end frames, an impression roller journaled in said arm and adapted upon movement of said arm to be located in depressed or released position, a pinion associated

with said roller, and gearing carried by one of said end frames and meshing with said pinion, said gearing adapted to rotate said roller during linear movement of said carriage and upon movement of said arm to released or depressed position.

3. In a duplicating machine, a carriage comprising end frame members, a handle arm pivotally mounted within said end frames, an impression roller journaled in said arm and adapted upon movement of said arm to be located in depressed or released position, and gearing carried by said carriage and operatively connected with said roller, said gearing adapted to rotate said roller during movements of the same into depressed or released position.

4. In a duplicating machine, a carriage comprising end frame members, a handle arm pivotally mounted within said end frames, an impression roller journaled in said handle arm, a pinion secured to said roller, gearing carried by one of said end frame members and associated with said pinion, and means for driving said gearing upon linear movement of said carriage and upon pivotal movement of said handle arm.

5. In a duplicating machine, a traveling platen carriage, an impression roller journaled therein, a pressure roller also rotatably mounted in the carriage, said impression roller mounted for movement into operative and inoperative positions with respect to the pressure roller, and gearing operative to rotate the impression roller upon linear movement of the carriage, said rotation occurring irrespective of the positions of the impression roller.

6. In a duplicating machine, a traveling platen carriage, an impression roller journaled therein, a pressure roller also rotatably mounted in the carriage, said impression roller having operative and inoperative positions with respect to the pressure roller, gearing operatively connecting the impression roller with means located on a part of the machine, said gearing rotating the impression roller upon linear movement of the carriage, and being also operative when the carriage is stationary to cause rotation of the impression roller upon locating the roller from operative to inoperative position or vice versa.

7. In a duplicating machine, a frame having a duplicating surface, a carriage for movement over the surface, an impression roller journaled in the carriage, gearing operatively connecting the roller with means on the frame, said gearing rotating the roller upon linear movement of the carriage, the gearing being operative to rotate the roller at a peripheral speed slightly less than the roller would have by reason of the linear movement of the carriage.

8. In a duplicating machine, a frame having a duplicating surface, a carriage for movement over the surface, an impression roller journaled in the carriage, a pressure roller also mounted for rotation in the carriage, said rollers operating on a sheet therebetween to impress the same on the duplicating surface, gearing operatively connecting the impression roller with means on the frame, whereby the roller is rotated upon linear movement of the carriage, said gearing rotating said roller with a peripheral speed such that tension is maintained on the sheet as it is impressed on the duplicating surface.

9. In a duplicating machine, a frame having a duplicating surface, a carriage for movement over the surface, an impression roller journaled in the carriage, said roller being pivotally associated

with the carriage and having an operative and in-operative position with respect to the duplicating surface, gearing connecting the roller with means on the frame, whereby the roller is rotated during linear movement of the carriage, said gearing also causing rotation of the roller when the same is oscillated from inoperative to operative position or vice versa.

10. In a duplicating machine, a frame having a duplicating surface, a carriage for movement over the surface, a rotatable impression roller, means pivoting said impression roller in said carriage on an axis spaced from its axis of rotation, a rack extending longitudinally of said frame, a gear meshing with said rack, the axis of rotation of said gear being coincident with the pivotal axis of said impression roller, and means driven by said gear for driving said impression roller.

11. In a duplicating machine, a frame having a duplicating surface, a carriage for movement over the surface, a rotatable impression roller, means pivoting said impression roller in said carriage on an axis spaced from its axis of rotation, a pressure roller co-operating with said impression roller, a rack extending longitudinally of said frame, a gear meshing with said rack, the axis of rotation of said gear being coincident with the pivotal axis of said impression roller, and means driven by said gear for driving said impression roller.

12. In a duplicating machine, a frame having a duplicating surface, a carriage for movement over the surface, a yoke pivoted in said carriage, an impression roller rotatably journaled in said yoke, the axis of rotation of said impression roller being spaced from the pivotal axis of said yoke, a rack extending longitudinally of said machine, a gear meshing with said rack, said gear having an axis of rotation coincident with the pivotal axis of said yoke, and means driven by said gear for driving said impression roller.

13. In a duplicating machine, a frame having a duplicating surface, a carriage for movement over the surface, a rotatable impression roller, means for pivoting said impression roller in said carriage for swinging movement around an axis spaced from its axis of rotation, a slide rod extending longitudinally of said machine and ro-

tatable around its longitudinal axis, said carriage being slidable as a unit along said slide rod and said slide rod being provided with rack teeth, a gear meshing with said rack teeth, means slideable on said slide rod and journaling said gear, said gear having its axis of rotation coincident with the pivotal axis around which said impression roller is swung, and means driven by said gear for driving said impression roller.

14. In a duplicating machine, a frame having a duplicating surface, a carriage for movement over the surface, a yoke provided in said carriage, an impression roller rotatably journaled in said yoke, the axis of rotation of said impression roller being spaced from the pivotal axis of said yoke, a slide rod extending longitudinally of said frame, means on said frame journaling said slide rod for rotation around an axis extending longitudinally of said frame, said carriage being slidable as a unit along said slide rod, rack teeth formed upon said slide rod, a gear meshing with said rack teeth, a member slideable on said slide rod and journaling said gear, said gear having an axis of rotation coincident with the pivotal axis of said yoke, and means driven by said gear for driving said impression roller.

15. In a duplicating machine, a frame having a duplicating surface, a rotatable slide rod extending longitudinally of said frame and provided with rack teeth, a carriage slidable on said rod for movement over said duplicating surface, a yoke pivoted in said carriage, an impression roller rotatably journaled in said yoke, the axis of rotation of said impression roller being spaced from the pivotal axis of said yoke, a rack extending longitudinally of said machine, a gear meshing with said rack, said gear having an axis of rotation coincident with the pivotal axis of said yoke, a member slideable on said sliding rod and constrained to rotate therewith, a shaft journaled in said member, a gear fixed to said shaft and meshing with said rack teeth, a second gear fixed to said shaft, the axis of rotation of said shaft being coincident with the pivotal axis of said yoke, a third gear rotatably journaled on said carriage and meshing with said second gear, and a fourth gear constrained to rotate with said platen roller and meshing with said third gear.
